UNITED STATES PATENT OFFICE.

RUFUS F. THOMPSON, OF YOUNGSTOWN, OHIO.

DESIGN FOR A BADGE.

SPECIFICATION forming part of Design No. 29,212, dated August 16, 1898.

Application filed February 3, 1897. Serial No. 621,893. Term of patent 14 years.

To all whom it may concern:

Be it known that I, RUFUS F. THOMPSON, a citizen of the United States, residing at Youngstown, in the county of Mahoning and State of Ohio, have invented and produced a certain new and original Design for Badges; and I do declare the following to be a full, clear, and exact description of the invention, such as will enable others skilled in the art to which it appertains to make and use the same.

My invention relates to a design for a badge; and it consists of a design for a badge of the configuration and arrangement shown in the accompanying drawing, in which the figure is a perspective view of a badge embodying my design.

The leading features of my design comprise an erect crescent with its horns pointing upwardly, and upon the middle of its base appears a six-pointed star, upon which is superimposed a circular disk.

Having thus fully described my invention, what I claim as new, and desire to secure by Letters Patent of the United States, is—

The design for a badge, substantially as herein shown and described.

In testimony whereof I hereunto affix my signature in presence of two witnesses.

RUFUS F. THOMPSON.

Witnesses:

J. T. CANFIELD,
ANNIE THOMPSON.
